Winslow Ames' Design for a Parlor Stove

Assigned to Harshorn, Ames & Co.

Patented November 1, 1853

Design No 607

Fig. 1.

U.S. 607

Winslow Ames, of Nashua, N. H.

Assignor to

Hartshorn, Ames, &c., of Boston, Mass.

Letters Patent No. 607. Dated Nov. 1st, 1853.

The schedule referred to in these Letters Patent, and making part of the same.

To all persons to whom these presents shall come:

Be it known that I, Winslow Ames, of Nashua, in the County of Hillsborough, and State of New Hampshire, have invented or produced a new ornamental design for a parlor stove, and I do hereby declare the same is fully described and represented in the following specification, and the accompanying drawings, letters, figures, and references thereof.

Figure 1 denotes a front elevation of the said design; Figure 2, a vertical and central section of the front plate, blower, and hearth; Figure 3, a vertical section of the front part of the top plate and water urn.

In the said drawings, A denotes the top plate or perforated dome extending up from a cornice D, and surmounted by a water urn B; and C is the blower which rests on the semi-vase D, which is to hold the fuel, and is made to project in alto-relievo from the front plate F. E is the hearth plate, which is supported by legs G, G. The front plate is flanked or ornamented on its sides by two sets of winged voluted scrolls, the lower of which are sprung from columnar and arched bases, while the inferior set is imposed on the superior scrolls.

Between the scrolls, and under the cornice D, the front plate F is ornamented in "bas-relief" by a tasseled and fringed curtain, which is looped up over the fire place or arch of the blower. A festooned cord and drops are suspended in bas-relief directly below each of the two cornices D and H. The blower is ornamented with a representation of three gothic windows surmounted with drapery looped with cords and tassels. The lower or vaulted part of the blower is formed with air openings, and from the upper part of the blower a handle K is extended. The remainder of the design, as well as the particular conformation of the details and ornaments which compose it, are clearly exhibited in the drawings, and so that a stove pattern maker, or designer of ordinary skill in his art will find no difficulty in comprehending the same.

I not only claim the ornamental design of the blower but that of the fire place front as exhibited in the accompanying drawings.

Exe. Witnesses,

J. F. R. R. H. Eddy, }
F. P. Hale, Jr. }

Winslow Ames.
